UNITED STATES PATENT OFFICE.

JOSEPH GRIEN, OF CHICAGO, ILLINOIS, ASSIGNOR TO HAMILTON-ROSS FACTORIES INC., A CORPORATION OF ILLINOIS.

DESIGN FOR A LAMP ARM.

Application filed October 8, 1927. Serial No. 23,692. Term of patent 7 years

To all whom it may concern:

Be it known that I, JOSEPH GRIEN, a citizen of the United States, residing at Chicago, in the county of Cook and State of Illinois, have invented a new, original, and ornamental Design for a Lamp Arm, of which the following is a specification, reference being had to the accompanying drawing, forming ing a part thereof, in which the figure is a front view of the lamp arm.

I claim:

The ornamental design for a lamp arm as shown.

In witness whereof I affix my signature.

JOSEPH GRIEN.
